UNITED STATES PATENT OFFICE.

ANTON I. HOVLAND, OF ST. PAUL, MINNESOTA.

TRACTION-ENGINE.

1,151,360.

Specification of Letters Patent. Patented Aug. 24, 1915.

Application filed November 14, 1910. Serial No. 592,402.

To all whom it may concern:

Be it known that I, ANTON I. HOVLAND, of St. Paul, Hennepin county, Minnesota, have invented certain new and useful Improvements in Traction-Engines, of which the following is a specification.

My invention relates to that class of traction apparatus wherein an endless belt is utilized for traction purposes and the object of the invention is to provide means for turning an apparatus of this kind easily and quickly and without the necessity of making a sweeping curve to reverse the direction of movement of the machine.

The invention consists generally in a traction machine having independent tractors on each side thereof, with a power device located on the frame of the apparatus and having connections with said tractors for driving the same simultaneously in the same direction, or driving either thereof in either direction while the other remains idle, with an elevator and turn-table device for relieving the weight of the apparatus on the tractors and throwing the same upon the turn-table during the turning operation.

Further the invention consists in various constructions and combinations, all as hereinafter described and particularly pointed out in the claims.

In the accompanying drawings forming part of this specification, Figure 1 is a side elevation of a traction plow apparatus embodying my invention, Fig. 2 is a plan view of the same, Fig. 3 is a horizontal sectional view illustrating the apparatus for operating the turn table device, Fig. 4 is a detail sectional view showing the construction of the turn table.

In the drawing, 2 represents the frame of the machine, wherein shafts 3 and 4 are mounted, corresponding shafts being provided at the opposite end of the machine, and sprocket wheels 5 and 6 are mounted on said shafts and around these sprocket wheels traction belts 7 and 8 are arranged, having friction shoes 9, preferably of channel bar iron, the flanges of which are adapted to dig into the soil and prevent slippage of the belts. These belts, as indicated, are preferably arranged in pairs, each pair being provided with a series of friction shoes, and the shafts of a belt on one side of the machine are movable independently of the shafts on the other side of the machine, so

that one belt can be driven forward or backward while the other one is stationary, or both can be driven simultaneously in either direction. The shafts of the traction belts are operated through chains 10 and 11 which connect sprockets 12 on the traction belt shafts with pinions 13 on a shaft 14 which is journaled in the frame of the machine. Clutch members 15 and 16 are provided on each side of a clutch gear 17 which meshes with a pinion 18 on a counter shaft 19 and through this pinion and counter shaft the turn table mechanism is operated and the plows raised or lowered, as will be herein-after described in detail. The clutch device forms the subject matter of a separate application and I make no claim to the same herein and do not show the details of construction. The clutch members are operable independently of one another by means of a rod 20 having an arm 21 secured thereon in position to engage and rock a crank arm 22 mounted on the clutch operating shaft 23. This rod is rocked by means of a lever 24. A sleeve 25 is carried by said rod and is provided with mechanism for operating the other clutch member similar to that described, and I will designate the parts by the same reference numeral with the addition of the exponent "a."

A lever 24 is mounted to rock the sleeve 25 on its supporting rod and actuate the clutch member 15. The clutch gear 17 is driven from a gear 26 on the crank shaft 27 of the source of motive power 28, which may be of any suitable design or type.

Upon the shaft 19 friction collars 29 are mounted and above these collars friction wheels 30 and 31 of suitable material are eccentrically mounted on shafts 32 and 32^a, so that when these shafts are rocked in their bearings the friction wheels 30 will be moved into or out of contact with the collars 29.

The eccentric shafts are rocked by independent means consisting, preferably, of rods 33 and 34 journaled in the machine frame and having treads 35 and 36 with links 37 and 38 connecting arms on said rods with cranks 39 on the eccentric shafts. The rocking of these shafts will move the friction wheels 30 and 31 into or out of engagement with their respective collars and cause the power from the shaft 19 to be transmitted through the friction wheels to operate

either the plows or the turn table mechanism.

The turn table mechanism is controlled by the friction wheel 30 through a belt 40 connecting the shaft 32 with a shaft 41 which is provided at its inner end with a pinion 42 meshing with a gear 43. This gear is loosely mounted and has clutch connections 44 and 45 with a centrally arranged clutch collar 46 splined on the shaft 41, said clutch collar being operated by a bar 47 and a lever 48. In the position shown in Fig. 3 both clutches are inoperative and the gear 43 is stationary. When the lever 48 is thrown 10 in one direction, one of the clutches will be thrown to its operative position to connect the shaft 41 and the gear 43 and cause the shaft to be driven in one direction. When the other clutch is operated, the shaft will 15 be driven in the opposite direction. This shaft controls the raising and lowering of the turn table device and the purpose of making it revolve either in one direction or the other is to permit the lowering of 20 the turn table to its operative position or the lifting of the same to its inoperative position.

Journalized in the frame of the machine is a series of upright screws 49, preferably 25 four in number, each having a sprocket wheel 50 thereon to engage a belt 51 operating in a horizontal plane and passing around these sprocket wheels and a similar sprocket wheel 52 on the shaft 52', upon 30 which the gear 43 is mounted. The sprocket wheels 50 have interiorly threaded hubs 53 thereon and are held against vertical movement on the screws 49 by cross bars 53' on the machine frame on the underside and by 35 a ring 54 on the upper side, which has anti-friction bearings 55 on the sprocket wheels. When, therefore, power is applied to the sprocket chain 51 through the shaft 41 and its connections with the eccentric shaft 32, 40 the sprocket wheels 50 will be revolved and the screws passing through them raised or lowered, according to the direction of revolution of the gear 43. The upper ends of the screws are held in proper parallel relation by means of a spider 56 and on the lower ends of the screws a casting 57 is mounted, forming the upper portion of the base of the turn table. The lower portion, 45 or the part that contacts with the ground, 50 represented by reference numeral 58 in Fig. 4, is composed of suitable material, preferably planking, which can be readily removed and renewed when worn. A ring 59 is mounted on the base 58 and anti-friction 55 rollers 60, journalized in rings 61 and 62, are interposed between the casting 57 and the base ring so that when the base is seated on the ground the superimposed casting may turn freely thereon and allow the machine 60 to be revolved and its direction of move-

ment easily and quickly changed. The casting 57 has a central bearing 62 in which a stud 63 formed on a hub 63' is journaled, the stud being secured in its bearing by a cap 64' fitting the threaded end of the stud. 70

In the operation of the turn table device, the friction wheel 30 will be moved into engagement with the friction collar to transmit power to the belt 40 and drive the shaft 41. The position of the clutch device in 75 connection with the gear 43 determines the direction of movement of said gear; one direction will revolve the screws in one way and force the base of the turn table downward to lift the machine sufficiently to throw 80 the greater portion of the weight upon the turn table, leaving sufficient contact only between the traction belts and the ground to allow one belt to be operated to turn the machine. If quick action is desired, one 85 traction belt may be moved in one direction, and the other belt in the other direction.

For the purpose of raising the plows before turning the machine, I provide a mechanism which I will now describe in detail. 90 64 represents the plow frame, 65 a series of plow beams connected thereto and carrying plows 66. This frame, as shown plainly in Fig. 2, is arranged diagonally with respect 95 to the direction of movement of the machine and each plow beam has a cable 67 leading therefrom to a lever 68 that is mounted on a shaft 69 carried by the machine frame. The cables 67 pass under suitable anti-friction wheels 70 and the levers 68 have anti-friction wheels 71 in the paths respectively of a series of cams 72 mounted on a shaft 73. These cams, while corresponding in 100 form, are arranged at different points on their shaft so that when the shaft is revolved the levers 68 will be actuated successively and the plows lifted out of the ground successively in a corresponding manner. A gear 74 is secured on the shaft 73 meshing 110 with a pinion 75 on a short shaft 76 that is mounted above the shaft 73 and carries a worm wheel 77 which meshes with a screw 78 having a beveled pinion 79 that meshes 115 with a gear 80 on a counter shaft 81. The counter shaft 81 is arranged parallel with the shaft 73 and is driven by a sprocket chain 82 from the shaft 32, the rocking of the shaft 32 to move the friction wheel 31 to its operative position being controlled by 120 the shaft 33 and the treadle 35. The revolution of the shaft 73 will revolve the cams 72 and successively lift the plows out of the ground when it is desired to move the machine across the field or change its direction of movement. The cams are so adjusted that the plows will be lifted successively as they reach a point opposite the end of the furrow of the foremost plow or, in other words, as the plows approach the end of the 125 130

land, the foremost plow will be lifted out of its furrow first and the succeeding plows successively raised as fast as they reach the end of the land. The result of this arrangement is that the end of the land will be straight and the furrows will be all of the same length. The device used for lifting the plows successively will also be utilized for lowering them in rotation.

It is also desirable to lift the plow frame and I therefore provide cranks 83 and 84 on the shaft 73 connected by links 85 and 86 with the plow frame. Draw-bars 87 connect the machine and plow frame and a series of guiding bars 87' are also provided and pivotally connected with the machine frame to hold the plow frame and prevent it from oscillating laterally when lifted. The connection of the link 85 with the plow frame may be made in any suitable way, but preferably through the bell crank 88 and the rod 89 connecting it with the plow frame. The plow frame attached directly to the traction apparatus is capable, as described, of swinging vertically to lift all of the plows out of the ground simultaneously. This is important in case it is desired to back the machine and particularly so when the plows have gathered up refuse or encountered some obstruction, and the driver wishes to back the traction apparatus and disengage the plows from the refuse or obstruction with which they may have come in contact. Other agricultural implements attached to the traction apparatus may be lifted to an inoperative position in substantially the same way.

I do not wish in this application to be confined to the mechanism herein shown and described for effecting the elevation of the machine, as I am aware that a turn table device of this kind can be constructed in many different ways and accomplish substantially the same result as I have attained and the driving connections, therefore, may also be modified in different ways and still be within the scope of my invention.

I have shown this turn table device used in connection with a traction machine having belts, but do not wish to confine myself to this use, as a similar mechanism will be found to be very advantageous in the turning of a traction machine having wheels instead of belts. Generally a large amount of space is required at the end of the land to be plowed for turning the traction apparatus, but with my invention a machine can be turned "in its tracks" or substantially so, and it is thus possible to plow with a machine of this type all of the land that is desired for cultivation instead of leaving the turning ground at each end of the land, as usually required, to be plowed by some other means.

I do not limit myself to the details of con-

struction herein shown and described, as the same may be varied in many particulars without departing from my invention.

I claim as my invention:

1. A traction machine, comprising, in combination, a supporting frame, tractors upon each side of said frame, a source of motive power mounted on said frame, connections between said motive power and said tractors for operating both tractors simultaneously in the same direction, or one in either direction while the other remains idle, a vertically movable turn-table device having a stationary base and an upper revolvable portion, and an operating mechanism therefor, substantially as described.

2. A traction machine, comprising, in combination, a supporting frame, traction belts upon each side of said frame for engaging the soil, a source of motive power mounted on said frame, connections between said motive power and said traction belts for operating both belts simultaneously in the same direction, or one in either direction while the other remains idle, a vertically movable turn-table device having a stationary base and an upper revolvable portion, and an operating mechanism therefor, substantially as described.

3. A traction machine comprising a frame, a source of motive power mounted thereon, tractor belts having driving connections with said source of motive power for operating both tractor belts simultaneously in the same direction, or one in either direction while the other remains idle, a turn table device carried by said frame and having a base adapted to be lowered into contact with the ground to lift said frame, said base consisting of a substantially horizontal plate having a flat under surface, driving means connecting said turn table device with said source of motive power and a clutch mechanism controlling said driving means.

4. A traction machine comprising a frame, a source of motive power thereon, tractor belts having driving connections with said source of motive power for operating said tractor belts simultaneously in the same direction, or one in either direction while the other remains idle, a turn table device consisting of a substantially horizontal plate adapted to rest upon the ground, screws attached to said plate and having bearings in said frame, and mechanism for revolving said bearings to raise or lower said plate.

5. A traction machine comprising a frame, a source of motive power thereon, traction belts carried by said frame, connections between said motive power and said tractor belts for operating both belts simultaneously in the same direction, or one belt in either direction while the other remains idle, a turn table device including a base adapted to be moved into contact with the ground

and rest thereon, the upper portion of said base being capable of revolving on the lower portion, and mechanism for raising or lowering said base.

5. 6. A traction engine comprising a supporting frame, a source of motive power thereon, traction belts carried by said frame, a turn table device, including a substantially horizontal base adapted to be moved into contact with the ground and rest thereon, screws mounted on said base and vertically movable on said frame, sprocket wheels mounted on said screws and held against vertical movement thereon, a driving belt for said sprocket wheels, and mechanism operatively connected with said source of motive power for driving said traction belts simultaneously in the same direction, or one in either direction while the other remains idle and means for revolving said screws.

7. A traction machine comprising a frame, a source of motive power thereon, traction means upon each side of the frame having driving connections with said source of motive power for operating both said traction means simultaneously in the same direction, or one means in either direction while the other remains idle, a turn table device including a base, screws mounted therein and having bearings in said frame, sprocket wheels mounted on said screws and having hubs contacting with said frame, a ring mounted on said screws and having an anti-friction bearing on said sprocket wheels, whereby said wheels will be held against vertical movement on said screws and the revolution of said wheels will cause said screws to move vertically, and a driving connection between said sprocket wheels and said source of motive power.

8. A traction machine including a supporting frame, traction means upon each side of the frame, a source of motive power having a driving connection with said traction means for operating both traction means simultaneously in the same direction, or one in either direction while the other remains idle, a turn table device including a base having a lower portion adapted to rest upon the ground, and a revolute upper portion arranged to turn freely on said lower portion, elevating screws connected with said base and having bearings in said frame, and means for revolving said screws to raise or lower said base.

9. A traction engine including traction belts having shoes adapted to engage the soil and means for driving said belts simultaneously in the same direction, or one in either direction while the other remains idle, a supporting frame, a turn table device including a substantially horizontal base provided with a flat bearing surface to engage the ground for elevating said frame and

means for operating said turn table device until the contact of said belts with the ground is sufficient only to revolve said machine when the belts are operated.

10. A traction engine comprising a frame, traction belts therefor having shoes adapted to engage the soil, a source of motive power mounted on said frame, mechanism connecting said source of motive power with said belts for operating either one of said belts independently of the other, a turn table device adapted to be moved downwardly into contact with the ground, mechanism for operating said turn table device from the source of motive power, said turn table device being adapted to lift said frame sufficiently to allow the engine to be turned by the operation of one of said belts.

11. A traction machine comprising a frame, a source of motive power thereon, traction belts having shoes to engage the soil and driving connections with said source of motive power, said driving connections being adapted to operate either one of said belts independently of the other belt, a turn table device comprising a base adapted to be lowered to rest upon the ground, and means for raising said frame and supporting it on said base until only the middle portion of said belts contact with the ground, the operation of one of said belts turning the frame on said turn table device.

12. A traction machine including a supporting frame, traction belts therefor, a source of motive power having a driving connection with said traction belts for operating both simultaneously in the same direction, or one in either direction while the other remains idle, and a turn table device having a lower stationary portion adapted to rest upon the ground and an upper revolute portion and means for raising and supporting said frame on said base.

13. A traction machine including a supporting frame, traction belts therefor, a source of motive power having a driving connection with said traction belts and operating to move both simultaneously in the same direction, or one in either direction while the other remains idle, a turn table device including a base having a lower portion provided with a broad bearing surface adapted to rest upon the ground and a revolute upper portion arranged to turn freely upon said lower portion, and means for elevating said frame and supporting it on said base.

14. A traction machine including a supporting frame, traction belts therefor, a source of motive power having a driving connection with said traction belts for operating said belts simultaneously in the same direction, or one in either direction while the other remains idle, a turn table de-

vice including a base having a lower portion adapted to rest upon the ground and a revolute upper portion having an anti-friction bearing upon said lower portion, means for raising or lowering said turn table device, and a driving connection between said source of power and said turn table device.

15. A traction machine comprising a frame, a source of motive power thereon, traction belts having driving connections with said source of motive power for operating both simultaneously in the same direction, or one in either direction while the other remains idle, a turn table device including a substantially horizontal base having a broad bearing surface on the ground, screws having bearings in said frame, and an anti-friction bearing on said base, a driving connection between said screws and said source of motive power, means permitting the vertical movement of said screws and preventing a corresponding movement of said driving connection.

20. 16. A traction machine, comprising, in combination, a supporting frame, traction means for each side of said frame, a source of motive power mounted on said frame, connections between said motive power and said traction means for operating both traction means simultaneously in the same direction, or one in either direction while the other remains idle, carrying frame connected to one end of said supporting frame, means located upon said supporting frame for raising and lowering said carrying frame, a turn-table device, carried by said supporting frame,

ing frame, comprising means adapted to be lowered to the ground, and means for raising said supporting frame, and relieving the traction means of the principal portion 40 of the weight of said machine, whereby the machine may be turned in either direction by power and the carrying frame swung around therewith.

17. A traction machine, comprising, in combination, a supporting frame, traction belts upon each side of said frame, a source of motive power mounted on said frame, connections between said motive power and said traction belts for operating both simultaneously in the same direction, or one in either direction while the other remains idle, a carrying frame connected at one end to said supporting frame, means located upon said supporting frame for raising and lowering said carrying frame, a turn-table device, carried by said supporting frame, comprising means adapted to be lowered to the ground, and means for raising said supporting frame and relieving said traction 55 belts of the principal portion of the weight of said machine, whereby the machine may be turned by power in either direction and the carrying frame swung around therewith.

In witness whereof, I have hereunto set my hand this 9th day of November 1910.

ANTON I. HOVLAND.

Witnesses:
